UNITED STATES PATENT OFFICE.

ALBERT S. KUX, OF CHICAGO, ILLINOIS.

SEALING-MACHINE.

1,264,308.

Specification of Letters Patent. Patented Apr. 30, 1918.

Application filed July 9, 1917. Serial No. 179,582.

To all whom it may concern:

Be it known that I, ALBERT S. KUX, a citizen of the United States, residing in Chicago, in the county of Cook and State of Illinois, have invented certain new and useful Improvements in Sealing-Machines, of which the following is a specification.

My invention refers to merchandising and particularly to a novel means of utilizing 10 gummed paper strips for securing the wrappings of bundles and the like.

Among the various means of securing wrappings of packages, bundles and the like is the means of employing strips of paper 15 having adhesive material on one side and mounted so that strips of different lengths might be taken therefrom for application to bundles of varying sizes. In a device for providing gummed strips as above described 20 the strip is usually furnished in a roll and suitably mounted in a frame work so that the free end of the strip may be led over a moistener which generally is in the form of a roller the lower part of which is in water 25 and over which the strip passes to be moistened by the rotation thereof as it is pulled thereover. It has been found that when a portion of the strip is torn off for use that there is no portion of the remaining strip 30 available to be grasped by the operator when a new portion is desired. Under such conditions the operator's fingers become moistened and consequently the bundle which he is wrapping becomes wet or perhaps soiled.

35 To overcome these and other well known objections, I have devised a novel means for feeding the strip forwardly a sufficient distance so that the end thereof may be grasped by the operator without bringing his fingers 40 in contact with the moistening roller and at the same time provide means to press the strip against the roller so that the gummed portion may be sufficiently moistened for application to the package.

45 Another object is to provide a feeding mechanism and means for directing the strip against the moistening roller so that coöperation therebetween may be effected.

50 A further object is to provide a feeding mechanism and a pressing mechanism so associated that the pressing mechanism will not force the strip against the moistening roller while the strip is being fed forwardly by the feeding mechanism.

These and other objects of my invention 55 will be more readily understood by reference to the drawings, wherein,—

Figure 1 is a side elevation of the device provided with the preferred embodiment of 60 my invention.

Fig. 2 is a top plan view of Fig. 1.

Fig. 3 is a fragmentary side elevation showing the feeding mechanism at the forward end of its feed stroke.

Fig. 4 is a fragmentary elevation of a 65 portion of the device showing the feeding mechanism at its normal position at rest the strip about to be pulled forward through the guides, and

Fig. 5 is a section on line 5—5 of Fig. 3. 70

The device consists of a frame member 10 having supports 11 and 12. The support 11 is continued upwardly above the top of the frame member 10 to form a shoulder 13 carrying bearings 14. Mounted within the 75 bearings 14 is a roller 15 on shaft 14^a which carries the gummed paper strips 16. Mounted on the frame member 10 in suitable bearings 17 is a roller 18 and coöperating with the under side thereof is a spring 19 for 80 guiding the strips 16 against the under side of the roller 18. Positioned at the forward end of the frame member 10 is a moistening roller 20 mounted in suitable journals 85 21 and adapted to rotate within a compartment 22 in which water is placed.

On the lower portion of the forward support 10 is pivoted the feeding mechanism which is formed of a substantially U-shaped member having legs 23 and 24 pivoted at 90 25 to the supports 12. The legs 23 and 24 are connected by top member 26. Pivoted to the legs 23 and 24 is a frame member having side members 27 and 28, and cross member 30, the pivotal connection being at the 95 upper portion of the U member at the point 31. An operating lever 32 may be attached to the member 30 if desired for the actuation thereof. A spring 33 connected to the side member 27 at 34 and at the outer end 100 to an extension 35 on the frame member 10 acts to maintain the feeding mechanism in retracted or normal position.

For preventing forward movement of the upper member of the feeding mechanism beyond the point 105 that is desirable shoulders or other suitable stops may be provided on the members 23, 24 and 27, 28. Pivoted on the frame 10 or

the legs 12 is the presser bar which comprises side members 35, 36, and cross or presser member 37. A spring 38 connected to the side bars 35, 36, and at the other end attached to the frame member 10 serve to hold the cross bar 37 against the upper surface of the moistening roller 20. Mounted on the frame and positioned slightly in the rear of the moistening roller 20 are guides 39 being provided with spaced rear edges to direct the gummed strips therethrough and constricted at their front edges forming an opening to serve as a cutting edge when a portion of the strip is torn off. As shown in Fig. 2 the inner portions of the arms 23, 24, are provided with lugs 40 carrying set screws 41 adapted to bear against the arms 35, 36, of the presser member so that when the feeding mechanism is moved forwardly the set screws will cause the presser bar 37 to be raised from engagement with the moistening roller 20. Proper adjustment of the set screws 41 will determine the instant at which the presser bar 37 is removed from the roller 20 and how long it is held away therefrom during the time of operation of the feeding mechanism.

Mounted on the shaft 14^a for vertical adjustment against the spool 15 are guide members 42 which are provided with vertically disposed slots to overlie the shaft 14^a on which the spool 15 rotates and are provided with spring member 43 adapted to hold the guides 42 against the roll of gummed strips 16. For positioning the guides 42 on the shaft 14^a to accommodate different widths of paper strips knurled members 44 are provided which will adjustably position guides 42 on the shaft 14^a.

The operation of the device is as follows: Strip paper 16 wound on spool 15 is mounted on the shaft 14^a and the shaft inserted in the shoulders 14. The free end of the strip is then fed through underneath the roller 18 between the roller and its spring pressed guide 19 forwardly between the member 30 of the upper portion of the feeding mechanism and the upper bar 26 of the lower portion, thence between the guides 39 and underneath the bar 37 of the presser member. Portion 16^a of the strip then extends beyond the presser member 37 and is ready to be grasped by the operator. When the portion 16^a has been torn off as shown in Fig. 4 by raising the portion 16^a against the cutting edge on the guides 39 the front end of the strip 16 will be at the cutting edge of the guides 39 behind the presser roll 37 and in an inconvenient place to be grasped by the operator. The handle 32 of the feeding mechanism is then moved forwardly quickly. The movement of the upper portion of the feeding mechanism causes the strips 16 to be grasped between the upper member 26 of the lower portion and the

lower member 30 of the upper portion thereby feeding the whole strip 16 forwardly through the guides 39. The instant the feeding mechanism is moved forwardly the presser bar is raised from against the moistening roll 20 so as to permit the ends of the strips 16 to be moved forward freely. When the feeding mechanism is in its forwardly position as shown in Fig. 3 the handle is released and the springs 33 quickly move the feeding mechanism back to normal position as shown in Figs. 1 and 4, leaving the strip advance as shown in Fig. 1 with a free end 16^a. The movement of the feeding mechanism to normal position permits the presser bar to be moved against the upper side of the strip 16^a and thus when the strip is pulled forwardly by the operator will cause the roller 20 to turn and moisten the under side of the strip 16. The co-operation between the presser bar 37 and the roller 20 is essential so that the pulling forward of the strip 16 by the end member 16^a will cause the roller 20 to turn and thus moisten the under side of said strip. Furthermore, the return of the feeding mechanism must be accomplished quickly for if a restraint be placed on the handle 32 while the mechanism is allowed to return to normal position, the strip 10 will be moved backwardly as the gripping between the members 28 and 30 will continue as long as any pressure on the handle 32 remains.

I claim:

1. In a device of the class described, the combination with a frame, of a moistening roller, adapted to moisten a gummed strip, means for feeding the strip forwardly, and means actuated by the feeding means for pressing the strip against the roller after the strip has been fed thereby, substantially as described.

2. In a device of the class described, means for feeding a strip, means for moistening the strip, means for directing the strip into contact with said moistening means, and means between the feeding and pressing means whereby the latter is moved out of engagement with the strip when the former is actuated, substantially as described.

3. In a device of the class described, the combination of means for feeding a strip, means for moistening said strip, means for pressing the strip against the moistening means and means between the feeding and pressing means whereby the latter is moved from pressing engagement with the strip while the feeder is moving the strip, substantially as described.

4. In a device of the class described, the combination of a strip holder, a guiding member having a cutting edge, a moistening roller, means for feeding a strip through the guide member and means operable by the feeding means for pressing the strip against

the moistening roller after the strip has been advanced by the feeding means, substantially as described.

5. In a device of the class described, the combination of a strip holder, a guiding member having a cutting edge, a moistening roller, means for feeding a strip through the guide member, and means operable by the feeding means for pressing the strip 10 against the moistening roller after the strip has been advanced by the feeding means, the feeding means being adapted to release the strip on return to normal position, substantially as described.

15 6. In a device of the class described, the combination of a strip holder, a guiding member having a cutting edge, a moistening roller, means for feeding a strip through the guide member, means operable by the 20 feeding means for pressing the strip against the moistening roller after the strip has been advanced by the feeding means, the feeding means being adapted to release the strip on return to normal position, and means associated with the feeding means and pressing means whereby the pressing means is moved from engagement with the roller while the strip is being fed, substantially as described.

7. In a device of the class described, the 30 combination of a guide member having a cutting edge, a moistening roller adapted to moisten a gummed strip, feeding means normally held out of engagement with the strip adapted when actuated, to feed the strip 35 by momentary engagement therewith, a presser bar normally retaining the strip against said moistening roller, and coöperating means between the feeder and the presser bar whereby the latter is moved from against 40 the roller to permit the strip to advance when the feeding mechanism is actuated, substantially as described.

8. In a device of the class described, the

combination of a frame, a roll supporting shaft, adjustable means on the shaft for receiving rolls of strip paper and the like, of less width than the shaft length, means for moistening the strip, guide means for directing the strip onto the moistening means, said means being provided with a severing edge, 50 means for feeding said strip through said guide means, means for pressing the strip into contact with the moistening means, and means associated with the feeding and pressing means for holding the latter out of 55 pressing engagement with the moistening means, substantially as described.

9. In a device of the class described, the combination of a frame, a roll supporting shaft, adjustable means thereon for receiving rolls of strip paper and the like, means for moistening the strip, guide means for directing the strip onto the moistening means, means for severing the strip, means for feeding said strip through said guide 60 means, means for pressing the strip into contact with the moistening means, and means associated with the feeding and pressing means for holding the latter out of pressing engagement with the moistening means. 70

10. In a device of the class described, the combination of a frame, a roll supporting shaft, adjustable means thereon for receiving rolls of strip paper and the like, means for moistening the strip, guide means for 75 directing the strip onto the moistening means, means for feeding said strip through said guide means, means for pressing the strip into contact with the moistening means, and means associated with the feeding and 80 pressing means for holding the latter out of pressing engagement with the moistening means.

Signed at Chicago, State of Illinois, this 6th day of July, A. D., 1917.
